UNITED STATES PATENT OFFICE.

FREDERICK E. GILBREATH AND WILLIAM E. WING, OF LURAY, KANSAS; SAID
GILBREATH ASSIGNOR TO SAID WING.

TESTING MACHINE FOR INFLATABLE TUBES.

Application filed May 21, 1927. Serial No. 193,266.

This invention relates to testing machines for inflatable tubes and it is an object of the invention to provide a device of this kind whereby a tube to be tested may be 5 readily submerged within a liquid and in a manner whereby the liability of wet hands, clothing and other inconvenient and disagreeable conditions are eliminated.

An additional object of the invention is 10 to provide a device of this kind comprising a liquid containing vat together with tube carrying means operable to submerge the tube within the liquid in the vat and whereby the tube is readily lifted out of the vat.

15 The invention consists in the details of construction and in the combination and arrangement of the several parts of our improved testing machine for inflatable tubes whereby certain important advantages are 20 attained and the device rendered simpler, less expensive and otherwise more convenient and advantageous for use, as will be hereinafter more fully set forth.

The novel features of our invention will 25 hereinafter be definitely claimed.

In order that our invention may be the better understood, we will now proceed to describe the same with reference to the accompanying drawings, wherein:—

30 Figure 1 is a view in side elevation of a testing machine constructed in accordance with an embodiment of our invention;

Figure 2 is a view in top plan of the structure as illustrated in Figure 1;

35 Figure 3 is an enlarged fragmentary view partly in vertical section and partly in elevation of the machine as herein disclosed, with certain of the parts positioned to submerge an inflatable body;

40 Figure 4 is a fragmentary view partly in section and partly in elevation illustrating means herein disclosed for holding the inflatable body in submergence.

Figure 5 illustrates a detail.

45 As herein disclosed, our improved testing machine comprises a supporting structure S upon which is mounted an annular tank or vat T of desired dimensions and capacity and which defines a relatively large central opening 1.

The supporting structure S, as herein disclosed, comprises a central vertical tubular member or post 2 which is shown as circular in cross section although it is to be under-

stood that such cross sectional configuration 55 may be square or otherwise as desired. The lower end portion of the member or post 2 has bolted, as at 3, or otherwise secured thereto the apex portions of the oppositely disposed substantially V-shaped members M. 60 Each of these members M preferably constitutes an angle iron. The outer or free extremities of the members M are connected by the brace rods 4.

The outer end portions of the members M 65 have bolted, as at 5, or otherwise secured thereto the lower end portions of the upstanding angle irons or legs 6 and the upper end portions of these irons or legs 6 are bolted, as at 7, or otherwise secured to the 70 outer extremities of the substantially V-shaped members M'. Each of these members M' has its apex portion bolted, as at 8, or otherwise secured to the upper portion of the member or post 2 and preferably constitutes an angle iron. By this means a rigid supporting structure S is provided and the tank T hereinbefore referred to is rested directly upon the upper members M. 75

The tank T has its top open and the upper 80 marginal portion of its outer side wall 9 is reinforced with a heavy rolled in wire or rod 10 while the upper portion of the inner wall 11 of the tank is reinforced by a flat hoop or band 12 preferably overlying 85 the outer face of the wall 11. This hoop or band 12 has bolted or otherwise fixed thereto at predetermined points therearound the upstanding brackets 14 each including spaced arms 15. Extending between the arms 15 of each of the brackets 14 and pivotally held thereto by a bolt 16 or the like is the central portion of an arm or rod 17. The outer portion of this rod 17 is provided with a fork 90 consisting of two vertically spaced curved arms or fingers 18 which are adapted to receive therebetween and effectively hold an inflatable body, such as an inner tube for a tire.

The inner end portion of each of the arms 100 or rods 17 is pivotally connected, as at 19, with the upper portion of an elongated rigid member or arm 20. This member or arm 20 extends downwardly and is pivotally engaged, as at 21, with an upstanding bracket 105 22 carried by a sleeve or collar 23. This sleeve or collar 23 surrounds the member or post 2 and is adapted to have sliding move-

ment along such member or post 2 in opposite directions.

Depending from one of the upper members M' of the supporting structure S is a rigid arm 24 to the lower portion of which is pivotally connected, as at 24, an intermediate portion of a lever 26. This pivotal connection 25 is at a predetermined point above the lowermost position of the sleeve or collar 23 and the inner portion of the lever 26 is operatively connected, as at 27, with an upstanding member 28 carried by the sleeve or collar 23. The outer end portion of the lever 26 extends beyond the supporting structure S and carries a pedal 29. By exerting downward pressure on the pedal 29, the inner end portion of the lever 26 will move upwardly carrying the collar or sleeve 23 upwardly of the member or post 2 resulting in the inflatable member or tube A carried by the forks 18 being submerged within the liquid in the tank T, thus enabling an effective testing of such tube or inflatable member and in a manner whereby the operator is not subjected to wet hands, clothing or kindred inconveniences.

When pressure is removed from the pedal 29 the weight of the sleeve or collar 23 plus the weight of the members or arms 20 will cause the forks 18 and the inflatable member or tube carried thereby to swing upwardly out of the tank. In other words, it is to be noted that the submergence of an inflatable member or tube is effected by the operator while the raising of such member or tube out of the tank is done automatically.

After the tube has been submerged and is returned to its raised position it is permitted to remain over the tank until the water or other liquid thereon has drained therefrom.

If, for any reason, it is desired to maintain the inflatable member or tube A in submergence for a considerable period of time, the outer portion of the lever 26 may be engaged with a toothed rack 30 or the like carried by one of the legs 6.

From the foregoing description it is thought to be obvious that a testing machine for inflatable tubes constructed in accordance with our invention is particularly well adapted for use by reason of the convenience and facility with which it may be assembled and operated, and it will also be obvious that our invention is susceptible of some change and modification without departing from the principles and spirit thereof and for this reason we do not wish to be understood as limiting ourselves to the precise arrangement and formation of the several parts herein shown in carrying out our invention in practice except as hereinafter claimed.

We claim:

35 1. A testing device for inflatable bodies

comprising, in combination, an annular tank defining a central opening and including side walls, arms pivotally connected with the inner side wall of the tank at predetermined points thereon, said arms being provided with forks overlying the tank and which are adapted to provide a mounting for the inflatable body to be tested, and means coacting with the opposite end portions of the arms for moving the arms to bring the body carried by the forks into submergence within a liquid in the tank and to raise the forks and body out of such liquid.

2. A testing device for inflatable bodies comprising, in combination, an annular tank defining a central opening and including side walls, arms pivotally connected with the inner side wall of the tank at predetermined points thereon, said arms being provided with forks overlying the tank and which are adapted to provide a mounting for the inflatable body to be tested, and means coacting with the opposite end portions of the arms for moving the arms to bring the body carried by the forks into submergence within a liquid in the tank and to raise the forks and body out of such liquid, said last named operation being automatic.

3. A testing device for inflatable bodies comprising, in combination, an annular tank defining a central opening and including side walls, arms pivotally connected with the inner side wall of the tank at predetermined points thereon, said arms being provided with forks overlying the tank and which are adapted to provide a mounting for the inflatable body to be tested, means coacting with the opposite end portions of the arms for moving the arms to bring the body carried by the forks into submergence within a liquid in the tank and to raise the forks and body out of such liquid, and means for locking the arms against movement when the inflatable body carried by the forks is in submergence.

4. A testing device for inflatable bodies comprising, in combination, an annular tank defining a central opening and including side walls, arms pivotally connected with the inner side wall of the tank at predetermined points thereon, said arms being provided with forks overlying the tank and which are adapted to provide a mounting for the inflatable body to be tested, and means coacting with the opposite end portions of the arms for moving the arms to bring the body carried by the forks into submergence within a liquid in the tank and to raise the forks and body out of such liquid, each of said forks comprising vertically spaced fingers.

5. A device for testing inflatable bodies comprising, in combination, an annular tank defining a central opening and including spaced side walls, arms mounted upon the in-

ner side wall at points therearound for swinging movement in a vertical direction, the outer end portions of the arms being provided with means to hold an inflatable body, and pedal operated means operatively engaged with the inner portions of the arms to move the inflatable body supported by the arms into submergence within a liquid in the tank.

10 6. A device for testing inflatable bodies comprising, in combination, an annular tank defining a central opening and including spaced side walls, arms mounted upon the inner side wall at points therearound for swinging movement in a vertical direction, the outer end portions of the arms being provided with means to hold an inflatable body, a vertically disposed member positioned at substantially the axial center of the opening defined by the tank, a sleeve 15 slideable on said member, rigid arms operatively engaged with the sleeve and the first named arms, and means for imparting movement to the sleeve along the member in a direction to swing the arms to move the inflatable member supported by said first named arms into submergence within a liquid in the tank.

20 25

7. A device for testing inflatable bodies comprising, in combination, an annular tank defining a central opening and including spaced side walls, arms mounted upon the inner side wall at points therearound for swinging movement in a vertical direction, the outer end portions of the arms being provided with means to hold an inflatable body, a vertically disposed member positioned at substantially the axial center of the opening defined by the tank, a sleeve 25 slideable on said member, rigid arms operatively engaged with the sleeve at the first named arms, and means for imparting movement to the sleeve along the member in a direction to swing the arms to move the inflatable member supported by said first named arms into submergence within a liquid in the tank, said sleeve and the second named arms being of sufficient weight to automatically maintain the first named arms in a position to hold the inflatable member supported by the first named arms above the tank.

In testimony whereof we hereunto affix our signatures.

FREDERICK E. GILBREATH.
WILLIAM E. WING.
